SERVO OPERATED ACTUATING DEVICES
Michael John Broad, Enfield, England, assignor to The
Plessey Company Limited, London, England, a British
company

Filed Mar. 27, 1961, Ser. No. 98,707
8 Claims. (Cl. 137—596.15)

This invention relates to fluid-pressure servo actuating devices and has for an object to provide an improved actuating device in which movement of a control or primary element requiring little actuating force produces, by servo action, movement of a fluid-pressure motor in a direction and by an amount determined by the movement of the primary element.

According to the invention the fluid-pressure motor comprises two piston elements acting against each other, fluid being admitted to both piston elements in parallel from a common source of fluid under pressure, and fixed metering apertures being provided in the respective admission lines to each piston element, while fluid is allowed to spill from each of these admission lines through two variable ports of which one is controlled by the control element and the other by a feed-back element operated in such direction by the movement of the piston elements that the movement of the piston elements as a result of a displacement of the control element will alter the sizes of the apertures controlled by the feed-back element in the opposite sense to that in which the sizes of the other apertures have been altered by the movement of the control element. The two apertures cooperating with the control element may be arranged on a flat surface at one side and the two apertures co-operating with the feed-back element on a second flat surface at the opposite side, of a valve seat member, the control element and the feed-back element being formed as rotatable, approximately D-shaped plates respectively co-operating with the two said surfaces of the valve-seat member, or alternatively said apertures may be provided in an internal or external surface of revolution, for example in a cylindrical surface or in co-axial cylindrical surfaces, the orifices controlled by the feed-back element being axially displaced in the direction of the cylinder axis from the orifices controlled by the control element, while the control element and feed-back element are constituted by rotary slide elements of complementary shapes cooperating with the said surface or surfaces. In each case the movement of the control element in one direction will cause the pressure acting on one of the piston elements to rise and the pressure acting on the other to fall, thus producing forward movement of one and reverse movement of the other piston element until the resultant displacement of the feed-back element has produced equal and opposite variation of the apertures controlled by the latter, thus again equalising the pressure acting on the two piston elements. Since the movements of the control and feed-back elements are rotary, it is possible, by simply placing the apertures respectively controlled by the control element and the feed-back element at different distances from the axis of rotation while making them of equal size, to arrange for the angular movements of the feed-back element to be a multiple or a fraction of the movements of the control element.

The piston arrangement may be utilised as a flow-control device governing the flow from a source of pressure to, and the release of pressure fluid from a load, or the simultaneous admission of fluid under pressure to one, and its return from another load or vice versa. The volumes of flow controlled in this manner may be many times greater than those which can be controlled directly by the control element. The two loads may be respectively con-

2

stituted by the two sides of a hydraulic motor which operates in one direction or the other according as hydraulic fluid is admitted to one and allowed to escape from the other side or vice versa.

5 In the drawing accompanying the specification,

FIGURE 1 is a somewhat diagrammatic sectional elevation, in section on line 1—1 of FIGURE 2, of one embodiment of the invention in which the two piston members serve as secondary flow-control elements, operate in parallel bores, and act upon, and are coupled together by, a rocker member constituting the feed-back element,

FIGURE 2 is a section on line 2—2 of FIGURE 1,

FIGURES 3 and 4 are respectively an elevation, in section on line 3—3 of FIGURE 4, and a section on line 4—4 of FIGURE 3, of a modified embodiment,

10 FIGURE 5 is an enlarged cross-section of the control device of the said modified embodiment, and

15 FIGURE 6 is an enlarged somewhat diagrammatic perspective view thereof,

20 FIGURE 7 is a diagrammatic elevation of a modification of the embodiment illustrated in FIGURE 1 in section along the axes of the piston elements, and

25 FIGURE 8 is a perspective view, partly broken away, of a modified control device, which may be substituted for that of the embodiment illustrated in FIGURES 3 to 6.

30 Referring now first to FIGURES 1 and 2, the device according to the invention comprises a housing 1 having two parallel cylinder bores 2 and 3 of equal diameter accommodating piston members 4 and 5 respectively acting on a rocking platform 6 at opposite sides of the axis of the latter. The housing is provided with an inlet 7 for the hydraulic liquid, from which two passages 8 and 9 branch off which respectively, through fixed metering orifices 10 and 11, lead to the cylinder bores 2 and 3. 35 Branch lines 12 and 13 respectively lead from each passage 8 and 9 to two equal-sized ports 14 and 15 or 16 and 17 on opposite flat valve seat surfaces 18 and 19 of a valve seat member 20. An approximately D-shaped plate 21, hereinafter called D-plate, and acting as 40 the valve element slides sealingly on the seat surface 18. It constitutes the control member and is coupled by a shaft 22 to a diagrammatically indicated electric torque motor 23 by which it is turned in one direction or the other by a variable angle according to the intensity and 45 direction of the torque produced by the motor. A similar and oppositely facing valve plate 24, attached to the rocking member 6, slides sealingly on the opposite valve face 19 of the valve-seat member 20 and constitutes the feed-back member. In the drawing a small gap is left between 50 surfaces 18 and 19 and the surfaces sliding thereon, to show the individual elements more clearly. The ports 14, 16 which co-operate with the control valve member 21 are spaced further from the common axis of the shaft 22 and the rocker 6 than the ports 15 and 17 which co- 55 operate with the feed-back member 24, and the housing 1 is further provided with a drain aperture 25 for the withdrawal of liquid that has spilled through the apertures 14, 15, 16 and 17. Furthermore, each of the piston members 4 and 5 is provided with a land 26 and 27 respectively 60 which not only guides the stem of the piston in its bore but also co-operates with a load outlet 28 or 29 to connect the latter either with a chamber enclosed between the piston proper 4 or 5 and its control land 26 or 27, or with a cavity 30 in the lower part of the housing 1, which 65 communicates with the drain aperture 25. The chamber formed between each piston and its control land communicates through a cross bore 31 with the inlet 7 for the hydraulic pressure liquid.

70 Assuming now that, due to operation of the electric torque motor 23, the D-plate 21 (i.e. the control element) has been turned by a small angle in an anti-clockwise di-

rection as seen in FIGURE 1. This will cause the exposed part of the opening of port 14 to be increased and that of port 16 to be correspondingly decreased, thus, increasing the flow through and the pressure drop in the metering orifice 10 and hence reducing the pressure in bore 12 which acts on piston element 4 and at the same time decreasing the flow through and the pressure drop in the orifice 11 and hence increasing the pressure in bore 13 which acts on piston element 5. Piston element 5 will move downwardly and turn the rocker 6 in a clockwise direction as seen in FIGURE 1, moving the piston 4 upwardly against the reduced pressure acting thereon. The resulting movement of the rocker 6 will turn the D-plate 24, i.e. the feed-back element, which is connected therewith, and will continue until, due to this movement of the D-plate 24, the part of port 15 not covered by the latter is decreased by the same amount by which the non-covered part of port 14 has been increased, and similarly the opening of port 17 has been increased by the same amount by which that of the port 16 was increased by the movement of the control plate 21. When this position is reached, the total outlet areas available at the outlet end of each of the bores 12 and 13 will again be equal, and the pressures in these bores and those acting on the piston elements 4 and 5 will therefore likewise be equal to each other thus terminating the movement of the piston elements. Such termination of the movement of the piston elements after a predetermined length of stroke is independent of the provision of any springs counteracting such movement, whereby the invention avoids the necessity of providing a pair of matched springs. Moreover, since only the difference between the pressure drops in orifices 10 and 11 is utilised, the operation of the device remains substantially unaffected if there is slight leakage between surfaces 18 and 19 and the surfaces sliding thereon. It is therefore possible to make the frictional resistance to movement of plate 21 very small, so that an appreciable output torque can be achieved with very little resistance to the movement of the torque motor 23. Furthermore it will be seen that the resulting movement of the rocker 6 at which the D-plate 24 (i.e. the feedback element) restores pressure balance and thus terminates further movement, is proportional to the original movement of the control element 21 but is proportionally greater in view of the fact that the radial distance of the ports 15 and 17 which are controlled by the feed-back D-plate 24, is smaller than that of the ports 14 and 16 controlled by the control element 21 so that since the diameters of the ports 14, 15, 16 and 17 are equal, a proportionally greater movement of the feed-back element 24 is necessary to produce the same variations in the non-covered cross-sections of ports 15 and 17 as have been produced in ports 14 and 16 by the original movement of the control element 21.

The displacement of the piston elements 4 and 5 just described also moves the lands 26 and 27. Land 27 moves downwardly so as to partly open load port 29 to the pressure chamber formed in cylinder bore 3 between the piston 5 proper and land 27, and thus to liquid admitted through inlet 7, while the movement of land 26 is upward and similarly permits a restricted flow from load connection 28 to drain chamber 30. Thus, if load lines 28 and 29 are connected to the two sides of a hydraulic motor, the operation just described will cause the hydraulic motor to rotate in a direction corresponding to a flow from 29 to 28 and at a speed dependent upon the amount of displacement of the control lands 27 and 26, while the displacement of pistons 4 and 5 in response to an oppositely directed angular displacement of control element 21 will cause the hydraulic motor to rotate in the opposite direction.

In each case when the control shaft is returned to its normal central position, pressure balance is again disturbed in the opposite direction and will eventually be restored when the rocker member 6 has likewise assumed its normal symmetrical position.

When it is preferred to use cylinder surfaces instead of flat surfaces for the control of pressures in branches 12 and 13, the two-face slide-valve assembly 20, 21, 24 may be replaced by a cylindrical valve assembly as is illustrated in FIGURES 3 to 6, in which corresponding elements bear the same reference numerals as in FIGURE 1, increased by 120. In this embodiment the two-sided flat body 20 of FIGURES 1 and 2 has been replaced by a stepped cylindrical body 140 the interior of which constitutes the drain housing 150, while the surfaces 138 and 139 of the stepped bore of this body replace the flat surfaces of the body 20 by co-operating respectively with rotary half-sleeves 141 and 144, of which the former is operated via shaft 142 by the torque motor 143, while the latter is operated by the pistons 124 and 125 via the rocking beam 126.

Assuming that the torque motor 143 has turned the half-sleeve 41 which constitutes the rotary control valve, by a small angle from its neutral position in a clockwise direction as seen in FIGURES 3 and 6, the leading edge (counting in the direction of displacement from the neutral position) of the half-sleeve 41 will cover a greater part of port 136 while its trailing edge will cover a smaller part of port 134 compared with the neutral position, with the result that the flow in line 133 is decreased and that in line 132 is increased. Since the former flow passes through restriction 131 on its way to port 136 and the latter passes through restriction 130 on its way to port 134, the consequence is a reduced pressure drop in the first-mentioned restriction and an increased pressure drop in the last-mentioned restriction. The pressure acting on piston 125 will therefore rise and that acting on piston 124 will decrease compared with the neutral position of the valve 141, thus causing the pistons to turn the beam 126 about its pivot axis in a clockwise direction. This rotary displacement of the beam 126 causes the leading edge of rotary valve 144 to cover a greater portion of port 135 and its trailing edge to clear a greater portion of port 137. The movement of the pistons and beam will continue until the increase in the available area of port 137 balances the reduction in the available area of port 136 and at the same time the decrease in the available area of port 135 will balance the increase in the available area of port 134, thus restoring the original flow conditions through restrictions 131 and 130 and thus the balance of the pressures acting respectively on pistons 125 and 124. The movement of the pistons is utilised, in exactly the manner described with reference to FIGURES 1 and 2, for the control of flow in the service lines 148 and 149 as will now be understood without further detailed description.

While two embodiments of the invention have hereinabove been described in some detail, various features of these embodiments may be modified within the scope of the present invention. Two particular modifications shall now be described with respective reference to FIGURES 7 and 8 of the accompanying drawing.

While in the embodiment illustrated in FIGURES 1 and 2 the two oppositely acting piston elements are arranged side by side and coupled by the rocker lever 6, FIGURE 7 illustrates an arrangement which in most other respects is similar to that illustrated in FIGURES 1 and 2, but in which the two fuel-control pistons are arranged in mutual axial alignment. Corresponding parts have been indicated by reference numerals which are distinguished from those used in FIGURES 1 and 2 by the addition of the letter *a*; the two ends of the duct 31 through which fluid pressure is admitted between the lands of each of the spool-type slide valves have been respectively marked 31a and 31b. It will be appreciated that elements not shown in FIGURE 4 are supposed to be constructed as shown in FIGURE 1, more particularly the connection of ducts 8a and 9a to the fluid pressure inlet 7 through restrictors such as shown at 10 and 11 in FIGURE 1 and the provision of ducts, such as ducts

12 and 13 of FIGURE 1, which lead from passages 2a and 9a to the ports controlled by members 21a and 24a.

FIGURE 8 illustrates a modified control device which may be substituted for that of the embodiment of the invention illustrated in FIGURES 3 to 6, and which avoids the need of providing a stepped bore. The stationary stepped sleeve 140 of FIGURES 3 to 6 is replaced by a cylindrical sleeve 40a which has a pair of control ports 34a, 36a spaced along one generatrix and a pair of feed-back ports 35a and 37a respectively in diametric opposition to the control ports. Two rotary valve elements 51 and 54 are arranged for rotation about a common axis, the one valve element 51 being fixed on the shaft 42a of the torque motor 23, and constituting the control valve element, while the feed-back valve element 54 is rigidly connected with a lever arm 6c the function of which corresponds to that of beam 126 in that it co-operates with a pair of pistons 64 and 65 acting upon it in opposition to each other. The ports 34a and 35a are connected with passage 132 and the ports 36a and 37a are connected with passage 133, while the connections between these passages and the pistons 64 and 65 and the co-operation of the pistons with the liquid supply and the service ports is identical to that described with reference to FIGURES 3 to 6 and need therefore not be described again.

In operation, assuming that the control valve element 51 has been turned by a small amount in a clockwise direction as seen in FIGURE 8, this will reduce the exposed area of port 37a and increase that of port 35a, thereby reducing the flow in passage 133 and the pressure drop in restriction 131 and increasing the flow in passage 132 and the pressure drop in restriction 130, so that piston 65 will advance and piston 64 will recede with the result that feed-back valve element 54 will also be moved in a clockwise direction so as to decrease the available cross-section of port 34a and increase that of port 36a. Since port 34a is connected in parallel with port 35a and port 36a in parallel with port 37a, equal pressure action upon the two pistons 64 and 65 will be restored when the exposed area of port 36a has been increased by the same amount by which that of port 37a was decreased and conversely the area of port 34a has been decreased by the same amount by which that of port 35a had previously been increased.

What I claim is:

1. A fluid pressure-servo-actuating device, comprising a fluid pressure motor having two piston elements acting in opposition to each other, fluid-pressure admission means leading to both piston elements in parallel, two fixed metering apertures, one in the respective admission line to each piston element, two spill passages each communicating with one of these admission lines at a point between the respective metering aperture and piston element and each including two parallel slide valve ports, a rotary control valve element which co-operates with one port, and a feed-back rotary valve element which co-operates with the other port of each spill passage, said control element and said feed-back element being each slidably movable across said ports, and each having two edges respectively co-operating with the ports of the two spill passages and facing respectively forwardly and backwardly in relation to the direction of movement of such element so that any movement of either element will increase the spill from one and reduce the spill from the other admission line, the feed-back element being so coupled with the fluid pressure motor that the pressure variation produced by a movement of the motor and feed-back element will oppose such movement of the motor.

2. An actuating device as claimed in claim 1, wherein the two ports co-operating with the control element are arranged on a flat surface at one side and the two apertures co-operating with the feed-back element on a second flat surface at the opposite side, of a valve seat member, the control element and the feed-back element being formed as approximately D-shaped plates respectively co-operating with the two said surfaces of the valve-seat member.

5 10 15 20 25 30 35 40 45 50 55 60

3. An actuating device as claimed in claim 1, wherein the two ports co-operating with the control element are provided in a surface of revolution, the orifices co-operating with the feed-back element being axially displaced in the direction of the axis of said surface from the orifices controlled by the control element, the control element and feed-back element being constituted by rotary slide elements of complementary shapes co-operating with the said surface.

4. An actuating device as claimed in claim 1, wherein the two ports co-operating with the control element are provided in a cylindrical sleeve, the orifices co-operating with the feed-back element being axially displaced in the direction of the cylinder axis from the orifices controlled by the control element, the control element and feed-back element being constituted by rotary slide elements of complementary shapes co-operating with the said surface.

5. An actuator device as claimed in claim 1, wherein the two ports co-operating with the control element are provided in a cylinder sleeve, the orifices co-operating with the feed-back element and the orifices controlled by the control element being respectively axially displaced from each other in the direction of the cylinder axis, and the orifices co-operating with the feed-back element being arranged in substantially diametric opposition to the orifices controlled by the control element, the control element and feed-back element being constituted by rotary slide elements of complementary shapes co-operating with the bore of said sleeve, each slide element having two axially adjacent portions respectively having control edges facing in opposite directions for respective co-operation with the two bores associated with the slide element.

6. Actuating device as claimed in claim 1, wherein the ports respectively controlled by the control element and the feed-back element are arranged at different distances from a common axis of rotation while making them of equal size, to arrange for the angular movements of the feed-back element to be a multiple or a fraction of the movements of the control element.

7. Actuating device as claimed in claim 1, wherein the fluid-pressure motor is constructed as a flow-control device governing the flow from a source of pressure to, and the release of pressure fluid from a load.

8. Actuating device as claimed in claim 1, wherein the fluid-pressure motor is constructed as a flow-control device governing the simultaneous admission of fluid under pressure to one, and its return from another load and vice versa.
